UNITED STATES PATENT OFFICE

EDWARD ELIAS VON TELL, OF GOTTERBORG, SWEDEN

CLAMPING MEANS

Application filed September 18, 1929, Serial No. 393,499, and in Sweden July 8, 1929.

This invention relates to means for securing a movable object in position by clamping it against a stationary member. Such a clamping action can be utilized for a plurality of purposes as for instance when securing a work piece to the chuck or face of a lathe, or the haul rope of a ship to the bitts, or a sliding window of an autocar or railway car or the like. Especially I prefer to use my improved clamping means to secure the tarpaulin over a ship's hatch cover.

One purpose of the improved clamping device is to provide a substitute for any loose wooden wedge or similar members which hitherto are frequently used for such clamping effect, and which loose wedges are rather apt to be laid aside and lost.

Another object of my invention is to provide a clamping means which always is ready for use and which can be operated by means of simple implements, but nevertheless with a high degree of effectivity.

A further object of my invention is a clamping device with a double safety in its clamping effect, viz. on the one hand the locking effect caused by the friction between the clamping member and the object to be clamped, and on the other hand the locking effect caused by the friction between the clamping member and the support for said member.

In order to obtain the purposes mentioned above I have designed my clamping device in the shape of an eccentric pivotable upon a pivot and provided with a lug or prong disposed in such a relation to the pivot that a lever turned about the same pivot will cooperate with said lug or prong so as to rotate the eccentric, and thereby affording the clamping action of the eccentric upon the object to be secured. In a preferred embodiment of the invention, the pivot is designed as a screw bolt the nut of which constitutes the hub of the lever which lastmentioned member is designed as a wrench to cooperate with said nut, so that the nut will be moved along the screw bolt pivot simultaneously with the rotating of the eccentric by means of the screw wrench lever operating the lug on the eccentric.

The combined or double safety effect obtained by locking the eccentric when clamping the object to be treated, increases considerably the usefulness of the device as it will prevent its nonintentional releasing even in case of large outer forces applied thereupon in an undue way.

In the accompanying drawing

Fig. 1 shows a vertical section through the hatch coaming with the improved clamping device also in section,

Fig. 2 shows a plan view of the parts in Fig. 1 whereby the wrench lever is drawn with full lines when in position to turn the eccentric, and with dot-and-dash lines when changed on the nut so as to come free from the lug on the eccentric when turning the nut.

Fig. 3 shows on a minor scale in elevation a portion of the hatch coaming viewed from outside, and provided with the improved clamping device, but with hatch cover and tarpaulin removed,

Fig. 4 on the same reduced scale as Fig. 3 a sectional plan view of the parts shown in said figure, and

Fig. 5 in section on a larger scale than Figs. 1 and 2 the upper portion of the pivot when designed as a screw bolt.

In the drawing 1 designates the ship's deck and 2 the hatch coaming which as usual on large hatches is reinforced by a big bulb iron 3. The hatch cover is designated with 4, and the tarpaulin which is spread thereabove in the usual way is designated with 5. The down hanging edges of the tarpaulin 5 are tightened to the side of the coaming, and the tarpaulin secured thereto by a clamping bar 6 which as usual runs along the side of the coaming, such a clamping bar 6 being provided along each of the four sides of the coaming.

In accordance with this invention each clamping bar 6 is pressed against the tarpaulin 5 and consequently the corresponding edge of the tarpaulin against the side of the hatch coaming 2 by means of an eccentric 7 which is rotatable about a vertical pivot 8 projecting upwards from the horizontal flange of the bulb iron 3, whereby the pivot 8 preferably is inserted through a hole in

said flange and stopped against the underside thereof by a head 12. Figs. 3 and 4 show a plurality of such eccentrics disposed along the sides of the hatch coaming on such distances as are necessary to suit the sizes of the 6 clamping bar 6 exactly as is the case with the wooden wedges hitherto used for the same purposes.

According to Fig. 1 the eccentric is composed of three parts viz. one centre part 9 which is the real clamping part, and two side parts 10 and 11 which serve to hold the part 9 between them. The centre part 9 may be constructed of a material which does not unduly wear and tear the clamping bar 6 but acts with necessary friction so as to secure the bar in clamped position. As such a material, can be utilized some hard wood, for instance beech, or any of the composite materials which are used in wheel brakes, auto-car couplings or similar devices. The side parts 10, 11 are made of iron or other metals and serve also as washers for the screw bolts which keep the parts 9, 10, 11 assembled without preventing their dismounting for renewing of the softer centre part 9. These assembling screw bolts comprise the pivot 8 which is designed as a screw bolt with head 12 and nut 13, and a screw bolt 14 arranged at some distance from the pivot 8, and provided with head 17 and nut 16. To facilitate the rotating of the eccentric, a washer 18 may be provided between the eccentric and the bulb iron 3 so as to reduce the friction between 35 said parts.

The lower washer 11 of the eccentric ought to have a larger periphery than that of the operative centre part 9, thereby constituting a bridge or shoulder 19 that projects outside the operative surface of part 9, and serves as a support for the clamping bar 6 before the bar has been clamped towards the hatch coaming. That will be clearly understood by Fig. 1. Naturally, if so wanted, 40 so the upper washer 10 can be designed in the similar way, thus forming a channel in which the clamping bar 6 will be more steadily secured.

When the tarpaulin is to be clamped between the bar 6 and the hatch coaming 2, a wrench 15 is laid on the nut 13 which wrench is provided with a tongue 20 projecting in the main direction of the wrench shaft 21 but on the opposite side of the jaws of the wrench. 50 The wrench then obtains the character of a double armed lever which when tightening the clamping bar 6 will be used as described in the following: The wrench is swung with the nut 13 until its tongue 20 contacts the 55 nut 16 or the projecting end of the bolt 14; a further swinging of wrench 15 now will make the eccentric 7 follow said motion on account of the wrench serving as a double armed lever pivoted around the bolt 8 and 60 acting on lug or prong 16 or 14 of the eccentric

by its short arm 20. The eccentric, as a consequence, is pressed with the operative surface of the centre part 9 against the clamping bar 6 which in its turn forces the down hanging edge of the tarpaulin tight against the hatch coaming 2. When said turning of the eccentric 7 has gone on so far as the force applied to the wrench shaft 21 is apt to clamp the tarpaulin between bar 6 and hatch coaming 2, the wrench 15 is removed off the nut 13 and shifted to another position thereupon so that its tongue 20 comes free of the nut 16—exemplified by the dot-and-dash lines in Fig. 2. When the wrench now is swung in the same direction as before there is nothing which prevents such a movement, and as a consequence the nut 13 without influencing the above mentioned position of the eccentric will be set on the bolt 8 so much as is necessary to tighten the eccentric downwards 85 against the supporting bulb iron 3, thus locking the eccentric in its clamping position and preventing its nonintentional releasing therefrom. The tightening of the tarpaulin thus is given a double safety, viz. at first, the friction arising between the curved surface of eccentric 7 and the clamping bar 6, and secondly, the friction between the underside of eccentric 7 and the bulb iron 3.

To release the tarpaulin one has to repeat the above mentioned operation but in opposite direction and order. At first the nut 13 is slackened up by means of the wrench 15 in such a position that its tongue 20 does not coact with the nut 16 or bolt 14, and thereafter the wrench 15 gets shifted on the nut 13 to a position in which its tongue 20 will operate the nut 16 or bolt 14 on the reverse side in comparison with that on Fig. 2, whereby a swinging of the wrench will cause the eccentric 7 to release its grip on the clamping bar 6.

When the wrench 15 is used simply as a lever with the tongue 20 operating the bolt 14, the nut 13 serves for a hub of the lever by means of which the lever will turn about the bolt 8 as a pivot. The single difference in comparison with an ordinary lever hub is, that the latter one will turn around a plainly cylindrical pin while the nut 13 during its rotating slides along the threads of the screw threaded bolt 8, but this difference executes an increased friction between hub and pivot according to the pressure between nut and bolt threads. Therefore it is necessary to provide for a good lubricating in order to prevent excessive loss of forces. For that purpose the nut 13 is provided with an automatic lubricating device shown in Fig. 5. The end of the bolt 8 has a central axial bore 22 which is screw threaded and closed by a screw plug 23 that can be screwed out and by means of a wrench or a screw driver. The axial bore 22 terminates in one or more radial bores 24 which terminate in the outer surface of the bolt 8 within the range of its threaded 115 120 125 130

portion that is in cooperation with the nut 13 when operative. If the cavity in the bolt end composed by the central bore 21 and the radial bore or bores 24 is filled with a lubricating grease, and the plug 23 is screwed inwards, the grease will be forced out through the radial bore or bores 24 on the cooperating threads of bolt 8 and nut 13 thus acting in the same way as a usual Stauffer compression grease cup always to keep the cooperating rubbing surfaces of nut and bolt in a thoroughly lubricated condition.

In its details my invention can be varied in many ways without interfering with its material points. For instance the pivot 8 does not necessarily have the shape of a screw bolt but can be a plain pin of the usual type whereby the wrench 15 will be replaced by a common lever. By this arrangement, however, the above mentioned advantage of the double locking effect will be lost. Also the eccentric 7 does not necessarily be composed of different parts such as the centre part 9 and the two outer washers 10, 11 but can be made of a solid piece in which case the assembling bolt 14 can be dispensed with and replaced by a lug or prong formed in any suitable way and projecting from the top side of the eccentric 7 so as to suit the cooperation with the tongue 20. Further it is immaterial that the bolt 14 or its substitute be disposed on such a side of the pivot 8 that the lever 15 must have the character of a double armed lever but it can be positioned on the opposite side of the pivot to cooperate with the shaft 21 proper. Thus the wrench will act as a single armed lever. If the pivot has the aforesaid character of a screw bolt such a single armed lever may be replaced by a common wrench which, of course, will reduce the installation costs but the need of force will be increased when operating the device, and hence I prefer to use a double armed lever just as described above. Further modifications in the design of the invention may be undertaken in due conformity with its various applications, and can be clearly understood by everybody skilled in the art without need to illustrate or describe them here.

Having thus particularly described and ascertained my improved clamping device and how it is to be performed, what I claim as new and want to protect by Letters Patent is:

1. A mechanical clamping device comprising a stationary base member, a pivot rigidly connected to said base member somewhat remote therefrom, an object provided to be clamped to said base member, an eccentric rotatable about said pivot so as to be swung against said object to clamp same against the base member, a lug on said eccentric spaced from said pivot, a lever provided to turn about said pivot, and to cooperate at some distance from its turning point with said lug

on the eccentric so as to forcibly turn the eccentric to clamp said object against the base member.

2. A mechanical clamping device comprising a stationary base member, a pivot rigidly connected to said base member somewhat remote therefrom, said pivot having the character of a screw bolt with nut, an object provided to be clamped to said base member, an eccentric rotatable about said screw bolt pivot, so as to be swung against said object to clamp same against the base member, a lug on said eccentric spaced from said pivot, a wrench provided to coact with said nut so as to turn the nut about the screw bolt, thereby adapted to cooperate at some distance from its turning point with said lug on the eccentric so as to forcibly turn the eccentric to clamp said object against the base member.

3. A mechanical clamping device comprising a stationary base member, a pivot rigidly connected to said base member somewhat remote therefrom, an object provided to be clamped to said base member, an eccentric rotatable about said pivot so as to be swung against said object to clamp same against the base member, said eccentric composed by an operative centre portion of some softer material and two metal side washers, said portions assembled by a throughgoing screw bolt, the end of which projecting above the one side washer forming a lug disposed somewhat remote from the turning point of the eccentric, a lever provided to turn about said pivot, and to cooperate at some distance from its turning point with said lug on the eccentric so as to forcibly turn the eccentric to clamp said object against the base member.

4. A mechanical clamping device comprising a stationary base member, a pivot rigidly connected to said base member somewhat remote therefrom, said pivot having the character of a screw bolt with nut, an object provided to be clamped to said base member, an eccentric rotatable about said screw bolt pivot, so as to be swung against said object to clamp same against the base member, said eccentric composed by an operative centre portion of some softer material and two metal side washers, said portions assembled by a throughgoing screw bolt, the end of which projects above the one side washer forming a lug disposed somewhat remote from the turning point of the eccentric, a wrench provided to coact with said nut so as to turn the nut about the screw bolt, thereby adapted to cooperate at some distance from its turning point with said lug on the eccentric so as to forcibly turn the eccentric to clamp said object against the base member.

5. A mechanical clamping device comprising a stationary base member, a pivot rigidly connected to said base member somewhat remote therefrom, an object provided to be clamped to said base member, an eccentric ro-

tatable about said pivot so as to be swung against said object to clamp same against the base member, said eccentric composed by an operative centre portion of some softer material and two metal side washers, said washers projecting outwards of said operative centre portion thereby forming a bridge for the support of the object to be treated.

6. A mechanical clamping device comprising a stationary base member, a pivot rigidly connected to said base member somewhat remote therefrom, said pivot having the character of a screw bolt with nut, an object provided to be clamped to said base member, an eccentric rotatable about said screw bolt pivot, so as to be swung against said object to clamp same against the base member, a lug on said eccentric spaced from said pivot, a wrench provided to coact with said nut so as to turn the nut about the screw bolt, thereby adapted to cooperate at some distance from its turning point with said lug on the eccentric so as to forcibly turn the eccentric to clamp said object against the base member, said screw bolt pivot having a central bore in the screw threaded end which bore is screw threaded and provided with a screw plug and terminates in one or more radial bores which terminates or terminate on the threaded surface of the bolt within the range of the nut of the bolt when operative, said central bore and radial bore or bores forming a cavity to be filled with a lubricant grease that by means of said screw plug can be forced out to the threads of the bolt so as to oil them when in cooperation with the nut such as can be done with a common compression grease cup.

7. A ship's hatch coaming, clamping bars along said hatch coaming provided to tighten a tarpaulin against said coaming, pivots rigidly secured along said coaming somewhat remote therefrom and conveniently spaced from each other, eccentrics pivotable about said pivots so as to tighten the tarpaulin against said hatch coaming and lugs on said eccentrics cooperating with levers pivotable about same pivots as the eccentrics to clamp the tarpaulin against the hatch coaming.

8. A mechanical clamping device comprising a stationary base member, a pivot rigidly connected to said base member somewhat remote therefrom, said pivot having the character of a screw bolt with nut, an object provided to be clamped to said base member, an eccentric rotatable about said screw bolt pivot, so as to be swung against said object to clamp same against the base member, a lug on said eccentric spaced from said pivot, a wrench provided to coact with said nut so as to turn the nut about the screw bolt, thereby adapted to cooperate at some distance from its turning point with said lug on the eccentric so as to forcibly turn the eccentric

to clamp said object against the base member, said wrench on the side of its jaws opposite to that of the shaft provided with a tongue adapted to cooperate with the lug on the eccentric when tightening or slackening up same, the shape of said tongue being such that the tongue comes out of contact with said lugs, if the wrench gets shifted on its nut whereby the nut can be tightened without turning the eccentric.

In testimony whereof I have affixed my signature.
